UNITED STATES PATENT OFFICE.

DAVID W. HARSHBARGER, OF MYERSBURG, PENNSYLVANIA.

IMPROVEMENT IN GRAIN SEPARATORS AND CLEANERS.

Specification forming part of Letters Patent No. **39,146**, dated July 7, 1863.

To all whom it may concern:

Be it known that I, DAVID W. HARSHBARGER, of Myersburg, in the county of Bradford and State of Pennsylvania, have invented certain new and useful Improvements in Machines for Hulling and Cleaning Grain; and I do hereby declare that the following is a full and exact description thereof, reference being had to the accompanying drawings, making part of this specification.

Figure 1 is a vertical section of my improved machine in the plane of the line *x x*, Fig. 3; Fig. 2, a vertical section of the same in the plane of line *y y*, Fig. 3; Fig. 3, a vertical section at right angles to the others in the plane of line *z z*, Figs. 1 and 2.

Like letters of reference indicate corresponding parts in all the figures.

A suitable frame, A, is provided having at the proper position on its top a grain-hopper, B, resting over a vibrating screen, C. The screen is connected at one end with a vibrating support, *a*, and at the opposite with a rock-lever, D, pivoted at *b*, and whose lower end forms a fork, *c*, resting over a cam-wheel, *d*. The shaft *e* of the cam-wheel receives its motion by a gear, E, engaging with a gear, F, on the main driving-spindle *G*. By this means the screen is vibrated forth and back, and the grain sifted through and separated from the coarser impurities—such as straw, &c. From the screen the grain falls into a conveyer, H, below its bottom *f*, opening into the eye of the upper hulling-stone, I, which rests on the end of the spindle *G*, while the bedstone *I'* is stationary. The stones are inclosed by a close circular curb, K, Figs. 1 and 3, which prevents the entrance of a current of air, except through the bottom *f* of the conveyer above. I make the acting surface of the upper stone concave, and the corresponding surface of the lower stone convex to fit. The stones are separated a greater or less distance, as may be desired, to adapt them to hulling different kinds of grain, or grain in different conditions, by raising or lowering the spindle *G*. To accomplish this easily, and without throwing the gear-wheels E F out of engagement, the lower end of the spindle rests in a beam, L, Figs. 1 and 3, hinged at *g*, and having a standard, *h*, which forms the inner bearing of the shaft *e* of the cam-wheel *d*. The opposite end of the beam has a rod, *i*, connected with it, and passing

upward through the frame, a hand-screw, *k*, screwing on its end to raise or lower it.

The arrangement of all the parts before described is very convenient, and enables me not only to screen the grain preparatory to hulling it, thus removing the coarser impurities, and to introduce it between the stones, but also to adjust the stones to any kind or condition of grain without disarranging or interfering in the least with the perfect working of the other parts. Thus as the beam L, supporting the revolving stone, is raised or lowered to produce the proper adjustment, the standard-bearing *h*, secured thereto, is correspondingly raised or lowered, thereby keeping the gears E F always in the same relative position, so that their engagement is never interrupted, and also preserving the relative connection of the cam-wheel *d* and rock-lever D, so that the screen will receive its reciprocations the same at all adjustments.

I do not claim merely producing an adjustment of the stones without disengaging the gearing, as I am aware that such an effect is produced in various relatives; but I do claim the arrangement and combination of all the parts composing the device having such a connection with the adjustment. The use of the screen and its connecting parts with the stones and adjusting-beam I believe to be new. By making the stones concave and convex, as described, I secure a great advantage over the flat-surfaced stones in ordinary use, for in the latter, there being no incline for carrying the grain off, it is subject to clogging, thus impeding the action by a very slow discharge, and the grain frequently becoming broken and crushed from the mass collecting between the stones. The incline between the stones in my arrangement produces a perfect discharge without clogging or crushing. This action is assisted by a draft of air (caused by a means hereinafter described) produced through the discharge-spout *l*, Fig. 3, which, opening between the stones, draws all the hulls and also all the grains out, thus keeping it perfectly clear. The spout *l* passes downward in an inclined direction, and opens into a chamber, M, which is provided with a revolving fan-beater, N, at a suitable position therein, and whose bottom is slightly inclined, and is made concave transversely, and is suitably perforated to allow dust and small seeds to pass through, as shown

most clearly in Figs. 2 and 3. Beneath the perforated bottom are two compartments, *n* and *o*, and at the lower end of the bottom is a third compartment, *p*. The first compartment, *n*, is for the passage of air; the second, *o*, for the reception of seeds and impurities that separate through the perforated bottom, and the last, *p*, for the reception of the cleaned grain. At the upper part of the chamber *M* at one end is an outlet, *g*, Fig. 2, communicating with a passage, *r*, extending upward, and opening into a case, *O*, which contains an exhaust-fan, *P*, the exhaust air escaping through an eduction-outlet, *s*, Fig. 3. The passage *r* below the outlet *g* forms a spout, *t*, for the escape of chaff, and if necessary the end of this spout may be covered by a valve to protect the draft. By this arrangement as the grain escapes from the hulling-stones through the spout *t*, it strikes the wings of the swiftly-revolving-beater *N*, which effectually scours it of all dirt and smut. It then falls on the inclined perforated bottom *m*, sliding gradually downward to the compartment *p*, into which it escapes, while the foreign seeds and impurities pass through the perforated bottom into the compartment *o*. While passing over the perforated bottom the grain is effectually stirred by the blast from the beater, which also acts as a fan, its effect being furthermore to create a draft through the spout *t*, between the hulling-stones, and still upward through the conveyer *H* and screen *C*, there being no inlet of air from any other source. Thus there is a constant draft through the grain from its entrance to its escape from the machine. This action is most effective in removing the dust and impurities from the grain, and also in keeping all the parts free and unobstructed, (and especially the stones, as before described,) as could not otherwise be done from the difficulty of reaching them. The curb *K* in particular would become filled around the stones

were there no draft to keep it clear. The intensity of the draft through the spout *t* is still further increased by the exhaust-fan *P*, which acts in conjunction with the fan *N*. In addition to this action it also serves another and essential purpose, which is to draw off the dust created by the beater in the chamber *M*, which dust would otherwise, from its intensity, settle down with the cleaned grain. An ordinary discharge-outlet would not be sufficient for the expelling of the dust, and, besides, it would allow an escape of the grain.

This machine is also adapted to separating grain aside from hulling.

What I claim as my invention, and desire to secure by Letters Patent, is—

1. The arrangement and combination of the concave and convex hulling-stones *I* *I'*, spindle *G*, adjusting-beam *L*, cam-wheel *d*, rock-lever *D*, vibrating screen *C*, and conveyer *H* in such a manner that the grain is screened and conveyed to the stones, and said stones are adjusted without affecting the action of the screen, substantially as herein set forth.

2. The fan-beater *N*, revolving in the chamber *M*, the perforated bottom *m*, compartments *n* *o* *p*, and the auxiliary exhaust-fan *P*, the two fan-chambers being connected by the passages *g* *r*, the whole arranged, combined, and operating substantially as and for the purposes specified.

3. The specific arrangement of the whole machine, whereby a draft is produced between the stones and through the grain from the time of its ingress to its exit, substantially as herein described.

In witness whereof I have hereunto signed my name in the presence of two subscribing witnesses.

DAVID W. HARSHBARGER.
